CLAIM

The ornamental design for an “arc light”, as shown and described.

DESCRIPTION

FIG. 1 is a right front top perspective view of the “arc light” design according to our invention;

FIG. 2 is a front elevational view of the “arc light” shown in FIG. 1;

FIG. 3 is a rear elevational view of the “arc light” shown in FIG. 1;

FIG. 4 is a bottom plan view of the “arc light” shown in FIG. 1;

FIG. 5 is a top plan view of the “arc light” shown in FIG. 1; FIG. 6 is a left elevational view of the “arc light” shown in FIG. 1;

FIG. 7 is a right elevational view of the “arc light” shown in FIG. 1; and,

FIG. 8 is a left front bottom perspective view of the “arc light” design according to our invention;

Portions of the “arc light” are shown in phantom lines and form no part of the design.

1 Claim, 3 Drawing Sheets(56)
